(57) **CLAIM**

The ornamental design for a shoe storage bench, as shown and described.

DESCRIPTION

FIG. 1 is a perspective view of a first embodiment of a shoe storage bench showing our new design;

FIG. 2 is a front view thereof;

FIG. 3 is a rear view thereof;

FIG. 4 is a left side view thereof, the right side view being a mirror image thereof;

FIG. 5 is a top view thereof;

FIG. 6 is a bottom view thereof.

FIG. 7 is a perspective view of a second embodiment of a shoe storage bench showing our new design;

FIG. 8 is a front view thereof;

FIG. 9 is a rear view thereof;

FIG. 10 is a left side view thereof, the right side view being a mirror image thereof;

FIG. 11 is a top view thereof; and,

FIG. 12 is a bottom view thereof.

The details of the shoe storage bench shown in broken lines form no part of the claimed design.

1 Claim, 12 Drawing Sheets
